Primary Examiner — Garth Rademaker*Assistant Examiner* — Fitzgerald L Butac(74) *Attorney, Agent, or Firm* — Prakash Nama; Global IP Services, PLLC(57) **CLAIM**

The ornamental design for a sensor light, as shown and described.

DESCRIPTION

FIG. 1 is a front elevational view of a sensor light showing my new design;

FIG. 2 is a rear elevational view in reduced scale thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

The broken lines seen in FIGS. 1, 6, and 7 show portions of a sensor light that form no part of the claimed design.

1 Claim, 7 Drawing Sheets(56)
